UNITED STATES PATENT OFFICE.

RALPH MAURIELL, OF OCEANPORT, NEW JERSEY.

SCALP-TREATMENT HOT-WATER CAP.

Application filed July 3, 1926. Serial No. 120,478.

This invention relates to a cap for a human head to be applied for scalp or hair treatment which comprises a flexible double walled receptacle to contain hot water by which application of heat to the hair and the scalp may be made. The heat is remedial in nature, promoting circulation of the blood and opening the pores of the skin; the resultant effect is beneficial in a number of ways; it applies heat all over the scalp, stimulates blood circulation with increased effusion in the scalp, increases the flow of perspiration, stimulates the hair follicles, produces a soothing effect on the individual using it, and relieves disorders due to poor blood circulation. Its aggregate result is invigorating to the scalp and hair. The essential features of the device is a waterproof double walled flexible crown to rest on the head and cover the hair, with reinforcements to maintain the walls from distorting in shape when filled with water, thereby permitting its more convenient use. The several features of construction will be herein after more fully described and the features of novelty definitely indicated in the appended claims.

In the drawing:

Figure 1 is a median vertical sectional view of an inflated cap.

Figure 2 is a transverse median section,

Figure 3 is a fragmentary section on plane X—Y of Figure 1, and

Figure 4 is a fragmentary vertical section through the filling neck.

Referring to the drawings in detail 1 and 2 represent counter-part walls of a flexible waterproof cap embodying my invention. The walls are continuous from the annular neck forming a filling orifice to the bottom wall 4. The material I prefer to use is soft vulcanized rubber, though other waterproof fabrics might be used. The neck 3 is reinforced by a vertical strip of rubber 5 terminating in a circular top with an open central seat for a water tight screw seated stopper 7; it also carries a dependent rubber post 8 terminating in a reinforcing strip 9 vulcanized to the under wall. The walls are spaced apart by a rib-like partition 10 extending from the neck dividing the walls and spacing them. A plurality of internal

studs 11 are vulcanized in place between the walls to hold them apart. The studs are six in number distributed symmetrically over the interior surfaces of the cap. When not in use the cap may be folded into comparatively small compass for storage but when filled with water it assumes an elliptical form and may be readily applied to the head for which it forms a mantle crowning a considerable portion of the scalp. The stopper is provided with a flexible chain to prevent its loss when out of service in applying the cap. The head is covered with a towel or napkin, and the cap filled with hot water is seated over the hair, and allowed to remain as long as desired or until the heat should be renewed by refilling.

The neck is so formed, that when the device is inverted all of the water will readily drain therefrom. To facilitate this drainage the inner end of the neck reinforcement 6 is flared as at 6'.

Having thus described my invention, what I claim and desire to secure by Letters Patent is:

1. A hot water bottle for the treatment of the scalp comprising a flexible dome shaped receptacle to form a cap for the head including double walls, a filling neck at one end of the receptacle communicating therewith between the walls and a vertical reinforcement extending from the bottom of the receptacle to the filling neck, and a stopper for the filling neck.

2. A hot water bottle for the treatment of the scalp comprising a flexible dome shaped receptacle including double walls adapted to form a cap for the head, a filling neck at one end of the receptacle communicating therewith between the wall, and reinforcing the filling plug in the neck, a stopper adapted to fit in said reinforcing plug, and a vertical reinforcement extending from the bottom of the receptacle to said filling plug.

3. A hot water bottle for the treatment of the scalp comprising a flexible dome shaped receptacle including double walls adapted to form a cap for the head, a filling neck at one end of the receptacle at the upper portion thereof, a longitudinal median portion vulcanized to the walls and between the same to act as a reinforcement

therefor, and a vertical reinforcement extending from the bottom of the receptacle to the filling neck and arranged in longitudinal alinement with said partition.

5. 4. A hot water bottle for the treatment of the scalp comprising a flexible dome shaped receptacle forming a cap for the head, and

reinforcements shaped to normally conform to the contour of the head arranged between the walls of the receptacle to facilitate the ¹⁰ fitting of the cap over the head of the user.

In testimony whereof I affix my signature.

RALPH MAURIELL.
